RAILWAY DUMP CAR

Carl P. Astrom, East Orange, N. J., assignor to
 M. H. Treadwell Company, Inc., New York,
 N. Y., a corporation of New York

Application December 5, 1942, Serial No. 467,932

3 Claims. (Cl. 105—265)

The invention relates to railway cars having tilting containers, such as cinder cars and the like. More particularly, it is concerned with locking means for the transversely movable actuating cylinder of the tilting mechanism of such cars.

The type of tilting container car to which my invention is particularly applicable has its tilting mechanism actuated by steam or compressed air, having a pressure cylinder arranged for movement transversely of the car to control the tilting of the container (or containers). In order to avoid accidental operation of the tilting mechanism, or tilting of the container through neglecting to use the conventional hand operated locking device, it is desirable to provide other means for locking the container in its upright position. The locking of the tilting mechanism has been accomplished heretofore by inserting a locking pin in front of a lug on the pressure cylinder to prevent movement thereof in that direction which would produce tilting of the container. A serious disadvantage of this arrangement is that locking of the mechanism depends upon the operator inserting the locking pin each time upon completion of the dumping operation and the return of the container to its upright position. There is nothing to insure that the locking operation will be performed as intended, and thus a definite hazard is presented in the possibility of premature tilting of the container. This becomes a matter of particularly serious concern when the cars are designed for the handling of molten slag, hot cinders or the like, where accidental tilting of the containers would endanger life and property. Accordingly, it is an object of my invention to provide a more fool-proof locking device which will eliminate the disadvantages of locking devices used heretofore.

Another object of my invention is to provide a locking mechanism of the class described which is adapted to be used in conjunction with existing types of tilting mechanism without substantial alteration thereof.

Other objects and advantages of the invention will appear as the description proceeds.

In my prior patent, No. 1,613,153, granted January 4, 1927, there is shown a railway dump car having a screw-operated dumping mechanism. My present invention is applicable to cars of this general type, but with a pressure cylinder form of dumping mechanism. Fig. 1 of the accompanying drawings is an end elevational view of such a car having a compressed air cylinder form of mechanism for actuating the tilting con-

tainer, and illustrates the application thereto of a preferred embodiment of my improved locking mechanism.

Fig. 2 is a side elevational view, partly in vertical section, of one end of the car, taken as shown at 2—2 in Fig. 1, looking toward the end of the pressure cylinder of the actuating mechanism. Details of the car underframe and container mounting are not shown, as they form no part of the present invention. For such general construction, reference may be had to my prior Patent No. 1,613,153, aforesaid, or to my application Serial No. 454,117, filed August 8, 1942.

Fig. 3 is a detail cross-sectional view taken on the line 3—3 of Fig. 1.

Figs. 2 and 3 are drawn to the same scale, which is larger than the scale of Fig. 1.

With more particular reference to Fig. 1, I shall first describe the general construction and operation of the pressure-operated mechanism for tilting the container (or containers) indicated in broken lines at *a*. The underframe of the car is indicated generally at *1* and may be of any conventional construction. Mounted on the underframe are supports *2* carrying a transversely extending track *3* for a trunnion *4* secured to a bail *5* (Fig. 2) carrying the tilting container *a*. A similar track and trunnion is provided at the other side of the bail (not shown) as in the arrangement shown in my prior Patent No. 1,613,153 aforesaid. Adjacent the track *3* is a transversely arranged horizontal rack *6* arranged to mesh with a gear sector *7* affixed to the trunnion *4*. The gear sector *7* is provided with two eccentric cranks *8*, one of which is arranged to be driven by the pressure cylinder in a manner which will be described subsequently.

Also mounted on the underframe *1*, is a pair of supporting frames *9* which extend upwardly at each side of the car to carry the pressure cylinder and associated structure. Transversely extending guide rods *10* and *11* for the reciprocable pressure cylinder *12* tie the supporting frames *9* together, the guide rod *10* passing through apertures in the bosses *13* formed on the frames *9*, and having reduced and threaded end portions extending through the frames, where they are secured by nuts *14*, and the guide rod *11* having reduced and threaded end portions *15* extending through apertures in the upper end of the supporting frames *9*, where they are secured by the nuts *16*. The reciprocable pressure cylinder is provided with a pair of upwardly extending guide lugs *17* surrounding the guide rod *11*, and a pair of depending guide lugs *18*

surrounding the guide rod 10, the lugs 17 and 18 being slidably mounted on these guide rods so that the pressure cylinder 12 is movable transversely of the car from one side to the other. A stationary hollow piston rod 19 passes through the center of the cylinder 12, being secured at its end in suitable bosses 20 formed on the frames 9. The hollow rod 19 carries a stationary piston 21.

Movement of the cylinder 12 is controlled by suitable fluid pressure means. In the construction illustrated, this is provided by the compressed air (or steam) lines 22 connected to opposite ends of the hollow piston rod 19 and in communication therewith. The compressed air lines, or pipes, 22 extend downwardly and thence laterally, as at 23, to the center of the car, where they enter a four-way valve 24 of conventional construction. The valve 24 is connected at 25 to a source of compressed air 26 through a shut-off valve 27 having an operating element 28 adapted for engagement by a removable handle or wrench. The operating lever of the four-way valve 24 is shown at 29. When the handle 29 is in the central position illustrated, the ports are open, so that air flows through both of the lines 22, filling the spaces on each side of the piston 21 with air or steam as the case may be. To get the cylinder moving, the valve 29 is operated to bleed the air or steam from one side of the piston (from the left side as viewed in Fig. 3), whereupon the cylinder starts to move in a direction to tilt the container *a* (to the right as viewed in Fig. 3). Initial tilting movement of the container away from the vertical causes it to become top heavy, and it begins to tilt rapidly, increasing the pressure on that side of the piston from which fluid had been bled. This increase in pressure, through conventional control means, automatically closes a valve, and the remaining fluid creates a cushion which will stop the tilting movement of the container before it strikes the car frame. After the container has emptied, it is returned to its normal vertical position by operating the handle 29 of the valve 24 to cause the compressed fluid to enter the cylinder space at one side of the piston 29 (the left side as viewed in Fig. 3), while permitting discharge of the fluid at the other side.

Suitable means preferably are provided to permit operation of the valve 24 from one or both sides of the car, such as the handles 32 pivotally mounted in brackets 33 secured to the underframe and operatively connected to the valve handle 29 by connecting rods 34, as by means of a clevis 35 attached to the rod and pivotally secured to the handle 32 at 36. One of the rods 34 is pivotally secured to the lower end of the handle 29 at 37, and the second rod 34 is pivotally secured to the projecting end of the first rod at 38. It will be understood that one or the other of the operating handles may be omitted if desired.

The cylinder 12 is provided with a pair of horizontally extending lugs 39, 40 (Fig. 2) carrying a key or pair of keys 41 slidably engaging a sleeve 42 rotatably mounted on the crank 8 of the gear sector 7 previously described, providing a driving connection between the pressure cylinder 12 and the gear sector 7 so that as the cylinder moves, the gear sector is rotated, driving the gear sector along the rack 6 and carrying with it trunnion 4 of the bail 5 in which the container *a* is supported. When the cylinder 12 moves to the right from the position shown in Fig. 3, the container 8 thus is moved to the right and at the

same time tilted about the axis of the trunnion 4.

In my preferred arrangement, the keys 41 are removable from the lugs 39, 40, lifting out through an aperture 43 in the lugs 39 for which purpose 5 an upward extension 44 is provided on the pins. After the keys have been removed, the cylinder 12 may be moved to the right while the container *a* remains in its upright position shown, and the keys 44 reinserted in other apertures formed in 10 lugs 39, 40 at the opposite end of the cylinder so that arrangement can be made for tilting the container *a* to the other side of the car, i. e., to the left as viewed in Fig. 3. This arrangement is the same as that illustrated except that the starting 15 position of the cylinder 12 is reversed so that the cylinder is at the right when the container is in the vertical position illustrated.

The operating mechanism which has been described may be provided with a suitable cover or 20 shield 45 for deflecting falling material into the container *a* during loading of the car, this shield being conveniently mounted on the supporting frames 9 as by means of angle irons 46, 47, 48. The shield 45 or the supporting structure thereof, 25 such as the angle irons 48, form a convenient mounting for the operating mechanism of my improved locking means, the shaft 49 of which is arranged above the pressure cylinder 12, being journaled in bearings in the angle irons 48 at the 30 sides of the car, and in a bracket 50 which may conveniently be secured to the shield 45 near the center. Near the center of the shaft 49 is fixed an arm 51 which is pivotally secured at its outer end to one end of a locking member 52, the locking member being pivoted at its other end, as at 53, to a clamp 54 secured to the guide rod 11. The inner end of the locking member 52 is arranged to rest normally on the top of the guide rod 11 in front of the lug 17 associated with the 35 reciprocal cylinder 12, but is arranged to be raised above the lug 17 by means of the arm 51 upon rotation of the shaft 49. The connection between the arm 51 and the inner end of the locking member 52 may comprise a pair of upstanding lugs 55 fixed to the locking member, and a pin or bolt 56 passing through these lugs and the end of the arm 51. The aperture for the bolt 56 in either the arm 51 or the lugs 55 preferably is 40 elongated to permit vertical movement of the end of the locking member in a plane normal to the axis of the pivotal mounting 53. The clamp 54 may be formed in two complementary parts 54 and 54', as shown best in Fig. 2, the part 54' being provided with a pair of lugs 57 to receive the pivot pin or bolt 53 which passes through an 45 aperture in the locking member 52.

In my preferred construction, the shaft 49 of the lock operating means is arranged to be actuated from either end thereof so as to permit operation from either side of the car. For this purpose a crank arm 58 is fixed to each end of the shaft 49, and to the outer end of each arm 58 is secured a pull chain 59 terminating in a suitable handle 60. The handle 60 preferably 50 also is secured by a short length of chain 61 to a portion of the framework to prevent it from swinging out of place or becoming tangled in the mechanism. It will of course be understood that, if desired, one of the pull chains 59 and its associated crank 58 may be omitted.

It is believed that the operation of the invention will be understood from the preceding description of the various portions thereof, but its 55 operation will now be summarized briefly:

The drawings show container *a* locked in its upright position as during transportation of the car with the container loaded. If any condition arises which tends to permit movement of the cylinder *12* to the right as viewed in Fig. 3 before it is desired to tilt the container *a* for dumping of its contents, such movement is prevented by engagement of the lug *17* with the end of the locking member *52*. When it is desired to tilt the container (the power means being connected to a source of compressed air), the valve *27* is opened and the operator, standing at one side of the car, pulls down on the handle *60* to lift the locking member *52*, then by means of the handle *32* operates the valve *24* to produce movement of the pressure cylinder *12* to the right as viewed in Fig. 3. So soon as the lug *17* of the pressure cylinder passes under the end of the locking member *52*, he may release the handle *60*. At the conclusion of the dumping operation the operator again actuates the valve *24* by means of the handle *32*, this time to produce movement of the cylinder *12* to the left to return it to the position shown in the drawings. As the cylinder *12* moves to the left as viewed in Fig. 3, the lug *17* lifts the member *52* and when the cylinder reaches the limit of its movement, this locking member drops into the position shown in Fig. 3 without further attention from the operator. Thus there is no possibility of the operator neglecting to lock the mechanism when the container reaches its upright position.

The terms and expressions which I have employed are used in a descriptive and not a limiting sense, and I have no intention of excluding such

equivalents of the invention described, or of portions thereof, as fall within the purview of the claims.

I claim:

5. 1. In a railway car having a tilting container and power means including a cylinder recipro-
cable transversely of the car for actuating the tilting container, means for locking the container in upright position, said means comprising a member pivotally supported to drop in front of a portion of the cylinder when the cylinder reaches a position in which the container is upright, a shaft above the cylinder and extending trans-
versely of the car, an arm fixed to said shaft, said arm having a pivotal engagement with said pivotally supported member, and a crank for turning said shaft to release said locking means.
10. 2. A locking device for the transversely mov-
able actuating cylinder of the tilting container mechanism of a railway dump car, comprising a locking member pivotally supported to drop in front of a portion of the cylinder when the cyl-
inder reaches a position in which the container is upright, a shaft above the cylinder arranged in substantial parallelism therewith, an arm fixed to said shaft, said arm having a pivotal engage-
ment with the locking member, and a crank for turning said shaft to lift the locking member.
15. 3. A locking device of the construction set forth in claim 2, in which the locking member is ar-
ranged to be lifted by a lug on the cylinder as the cylinder moves in a direction to bring the container upright and to remain in front of said lug thereafter until manually lifted.

CARL P. ASTROM.
